UNITED STATES PATENT OFFICE.

EARLE A. LYNN, OF SPOKANE, WASHINGTON, ASSIGNOR TO SULLIVAN MACHINERY COMPANY, A CORPORATION OF MASSACHUSETTS.

WATER-INTERCEPTING MEANS.

Application filed June 18, 1920. Serial No. 389,975.

To all whom it may concern:

Be it known that I, EARLE A. LYNN, a citizen of the United States, residing at Spokane, in the county of Spokane and 5 State of Washington, have invented certain new and useful Improvements in Water-Intercepting Means, of which the following is a full, clear, and exact specification.

My invention relates to water intercepting means and particularly to water intercepting means for use on rock drilling devices.

An object of my invention is to provide an improved water intercepting device for 10 rock drills. A further object of my invention is to provide an improved water intercepting device especially adapted for attachment to rock drills of the stoping type. Further objects of my invention will appear 15 in the course of the accompanying specification and appended claims.

In the accompanying drawings I have shown for purposes of illustration two embodiments which my invention may assume 20 in practice.

In these drawings,—

Fig. 1 is a view partially in elevation and partially in section on a central plane through the forward end of the chuck and 25 rotation mechanism of a stoping drill.

Fig. 2 is a sectional view taken on the line 2—2 of Fig. 1.

Fig. 3 is a fragmentary view similar to Fig. 1 showing a second form which my invention may assume.

It is a well-known fact to those who are familiar with the operation of that type of rock drill known as self-rotating stopers that in drilling overhead holes or holes above 40 the horizontal there is a troublesome tendency of the cleansing fluid in flowing back out of the hole to run back down the steel and into the chuck mechanism. This results in a considerable throwing of the returning fluid because the chuck is rapidly 45 rotating and centrifugal force throws the liquid upon all who may be close to the drill. For the purpose of obviating this difficulty, I have provided improved means adapted for 50 attachment to said drills, operating to cause the returning liquid to fall straight down without incommodeing the drill runner in any degree.

Referring to the drawings, it will be noted 55 that I have shown the illustrative embodiment

of my invention for use on a drill of the stoping type. This drill comprises a motor of the percussive type, the forward end of which is indicated at 1. This motor is adapted to be fed with respect to the 60 working face in a well known manner by a feed cylinder mechanism (not shown). Within the motor there reciprocates a piston provided with a striking extension 2 which is adapted by means of straight 65 grooves 3 and spiral grooves 4 and cooperating mechanism to cause rotation of the chuck member 5. The chuck member comprises a bushing 6 with which the forward end of the striking bar cooperates, a chuck housing member 7, and a chuck member proper 8. Within the chuck housing member 7 is formed a chamber 9 within which a striking plug 10 is arranged. The chamber 9 is provided with outwardly and generally 70 downwardly directed passages 11 to permit the escape therefrom of fluid passing back down the drill steel. To impede throwing of this fluid an apron 12 directed nearly 75 straight downward surrounds the openings 80 of the passages. It has been found, however, that this apron is not universally satisfactory and that in very soft work the flow of liquid may be so copious as to wet the drill runner in a very short time. For the purpose 85 of preventing the throwing of this fluid by centrifugal force I have devised an attachment generally indicated by 13 (and formed of elastic sheet metal when used as shown in Fig. 1) which comprises a cup- 90 like member having a perforated bottom 14 and an annular side wall 15, the bottom 14 having a plurality of holes 16 formed therein to permit the flow of liquid out of said member. The sidewall 15 extends forwardly beyond the rear end of the apron and accordingly intercepts water thrown off 95 from the edge of the apron by centrifugal force. This device may be held in place upon the forward end of the drill motor by 100 its elasticity, being merely clamped in place by its inherent springiness, as shown in Fig. 1, or when the shape of the forward end of the drill motor will permit, as shown in Fig. 3, a pair of larger holes 17 may be provided, 105 these being adapted to receive the side rods 18 and, being engaged by the heads 19 of such side rods, to hold the intercepting device in position. It will be evident that, in 110 the event that the water supplied to a hol-

low drill steel 20 by way of a usual water tube 21, or in any other manner, flows backward along the steel on issuing from the hole, this water, when it passes downwardly from the chamber within the chuck housing, will be intercepted upon its being thrown from the apron by centrifugal force and will then drop, due to the action of gravity, directly downward through the holes in the 10 intercepting attachment.

While I have in this application specifically described two forms which my invention may assume in practice, it will be understood that these forms of the same are 15 shown for purposes of illustration and that the invention may be modified and embodied in other forms without departing from its spirit or the scope of the appended claims.

What I claim as new and desire to secure 20 by Letters Patent is:

1. In combination with a rock drill having a rotating chuck and means for supplying cleansing fluid to a drill steel adapted to be received in said chuck, an attachment 25 comprising a perforated annular portion in a plane transverse to said drill elastically gripping a stationary portion of said drill, and a portion coaxial with said drill and adapted to intercept liquid returning along 30 said drill steel when the liquid is thrown by said chuck.

2. The combination with a drilling mech-

anism comprising a steel adapted to have longitudinal movement and allow a flow of fluid through the same, said mechanism having means for discharging a return flow of fluid along said steel, of means resiliently engageable with a portion of said mechanism and supported independently of said movable steel for deflecting said discharged fluid. 35

3. The combination with a drilling mechanism comprising a steel adapted to have longitudinal movement and allow a flow of fluid through the same, said mechanism having means for discharging a return flow 40 of fluid along said steel, of means including a split member resiliently engageable with a portion of said mechanism and supported independently of said movable steel for deflecting said discharged fluid. 45

4. The combination with a drilling mechanism comprising a steel adapted to have longitudinal movement and allow a flow of fluid through the same, said mechanism having means for discharging a return flow of 50 fluid along said steel, of means including a generally annular perforated split member resiliently engageable with a portion of said mechanism and supported independently of said movable steel for deflecting 55 said discharged fluid.

In testimony whereof I affix my signature.

EARLE A. LYNN.
